UNITED STATES PATENT OFFICE.

JAMES T. WETHERALD, OF BOSTON, MASSACHUSETTS.

DESIGN FOR A SYRINGE-NOZZLE.

SPECIFICATION forming part of Design No. 31,035, dated June 20, 1899.

Application filed May 5, 1899. Serial No. 715,745. Term of patent 14 years.

To all whom it may concern:

Be it known that I, JAMES T. WETHERALD, a citizen of the United States, residing in Boston, county of Suffolk, and State of Massachusetts, have invented and produced a new and original Design for Syringe-Nozzles, of which the following is a specification, reference being made to the accompanying drawing, forming a part thereof.

10 The drawing shows in side elevation my newly-designed syringe-nozzle.

The leading or material feature of my design consists in a syringe-nozzle of the shape shown provided with a cylindrical tapering body having thereon a number of oval-shaped concavities, each provided with a perforation within its boundaries.

a represents the cylindrical tapering body, *b* the oval-shaped concavities, and *c* the perforations within the boundaries of said oval-shaped concavities.

I claim—

The design for a syringe-nozzle, herein shown and described.

In testimony whereof I have signed my name to this specification in the presence of two subscribing witnesses.

JAMES T. WETHERALD.

Witnesses:

B. J. NOYES,
JENNIE L. HUTCHINSON.
